UNITED STATES PATENT OFFICE.

JAMES RUSSELL COUTTS, OF TORONTO, ONTARIO, CANADA, ASSIGNOR OF
ONE-HALF TO CHARLES AUBREY EATON, OF CLEVELAND, OHIO.

PROCESS OF GENERATING GAS.

No. 858,986.

Specification of Letters Patent.

Patented May 7, 1907.

Application filed January 10, 1906, Serial No. 206,988.

To all whom it may concern:

Be it known that I, JAMES RUSSELL COUTTS, residing at Toronto, in the Province of Ontario and Dominion of Canada, have 5 invented certain new and useful Improvements in Processes of Generating Gas, of which the following is a full, clear, and exact description, such as will enable others skilled in the art to which it appertains to make and 10 use the same.

This invention relates broadly to dry distillation processes and specifically it concerns certain improvements in processes of destructively distilling the various gramineous 15 products whereby superior yields of the resultant products are obtained.

One object of this invention is to formulate a commercially practicable method of distilling substances of the foregoing nature, 20 whereby the greatest possible yield of the most sought-for products of distillation will be obtained at a minimum of expense.

Another object of this invention is to utilize straw and the like in a process of destructive distillation in such a manner that valuable gaseous products may be obtained from matter which would ordinarily be wasted in 25 extensive agricultural districts.

This invention has in view, among other 30 objects, the adaptation of the art of dry distillation to straw so as to derive therefrom the maximum yield of gases rich in olefins and also distinguished by marked calorific power.

This invention, in general, seeks to provide 35 a process of the class described, which, from a commercial standpoint, will in practice possess a high degree of efficiency and effectiveness and which, chemically considered, will be of the greatest possible simplicity, 40 being composed of but few steps all adapted for being performed at a minimum of cost and individually of such nature as to be capable of being readily carried out, by any person skilled in the art, to accomplish the 45 purposes intended.

Other objects and advantages will be in part obvious and in part pointed out hereinafter.

The invention accordingly consists in the 50 several steps and the relation and order of one or more of such steps with relation to each of the others thereof which will be exemplified in the process hereinafter described

and the scope of the application of which will be indicated in the following claims.

In order that this invention may be more fully understood and made comprehensible to others skilled in its relating arts, a diagrammatic drawing illustrating a convenient manner of carrying out the same is appended 60 as a part of this specification, and, while the controlling principles of the invention may be otherwise applied by modifications falling within the scope of the claims, the herein disclosed embodiment is that which will ordinarily be preferable to employ in practice 65 and is regarded as representing substantial improvements over the many implied and obvious variations of the same.

The drawing shows an apparatus in general arrangement for carrying out the invention.

In the appended schematic drawing, corresponding parts are similarly referred to by like characters of reference, of which 1 indicates a mass of loose straw, which term I employ throughout as representative of the various equivalent gramineous products, such as are intended to be subjected to and take part in the improved process.

In carrying out this invention, it is preferable to preliminarily compress the straw into compact portions or bales, in order that its bulk will be reduced to the least possible space and divided into units so that the same 85 may be most conveniently handled, but it is to be understood that, while many advantages obtain from this preliminary compression, it is not absolutely essential in carrying out certain other steps of my process. To 90 that end, a press, as indicated on the drawing by 2, of any desirable construction or otherwise especially adapted for the purpose may be resorted to in order to compact the straw into bales 3 having the desired proportions. In this connection, it is to be observed that any preferred shape may be given these bales of compressed straw, but the 95 shape taken will conveniently be conformed to the selected form and proportions of distilling apparatus. A most advantageous form of bale for the purpose will consist in a relatively thin plate which may be of a rectangular shape adapted to be inserted in a retort of corresponding shape so that the heating flames may completely envelop the re-

retort along both broad faces thereof. By this means it is in some cases possible to insure a better application of the heat than where very thick masses are employed. The straw, as thus formed, is then subjected to distillation by means of an apparatus suitable for the purpose. In practice, a suitable conveyer 4 may be employed in order to conveniently transport the bales from the press to said apparatus.

This apparatus is adapted for the utilization of what has been found to be a highly important principle, namely, that by progressively heating successive portions of the straw, beginning at that portion adjacent the discharge pipe, so that the volatilized products will pass through the incandescent solid, carbonaceous skeleton preliminary to their discharge, the yield of permanent gaseous matter is very much enhanced both in quality and amount. Such apparatus comprises a furnace, designated by 5, provided with a distilling retort 6 and a suitably tight door 7 through which the straw bales may be admitted. A conduit 8 leads from the inner chamber to a suitable purification and collection apparatus, and a manhole 9 may also be provided in said retort to assist in obtaining access thereto for purposes of cleaning, repairing and the like. The heating of the retort may be accomplished by any preferred means, which is here schematically shown as consisting of a plurality of burners 10, 11, 12, 13, 14 and 15, each provided with suitable regulating cocks in order that they may be brought into effective action in the desired sequence, as will now be set forth. The basis of the distillation, that is to say, the bale of straw or the like, is so introduced into the retort as to be capable of being progressively subjected to the action of the heat within successive zones 16, 17, 18, 19, 20 and 21 throughout the length thereof by means of the aforesaid burners; the heating progressing from the discharge end. The furnace may also be provided with baffle plates 22 for insuring a complete circulation of the heated gases around the retort, and an exit for the waste gases is shown by 23.

In carrying out this process in practice, it is to be understood that it is immaterial whether the straw be translated through the apparatus in order to subject successive portions of it to the zones of high temperature, or whether the heated means be caused to change so as to heat successive portions of the straw within the retort. Thus, while an intermittent type of retort is shown, this invention furthermore contemplates the use of an apparatus of a continuing type so designed that the straw may be continuously fed through the retort and thereby obtain the desired effect.

The operation of the device in carrying out the process is as follows: A fresh charge of

straw is introduced into the retort and that burner 10, which is nearest the escape conduit 8, is ignited, resulting in a carbonizing of zone 16 to a complete degree and, perhaps, carbonizing the adjacent zone 17 to a relatively less degree. It will be noted in this connection that the gases from zone 17 are compelled to pass through the incandescent zone 16 before being enabled to escape through the conduit 8. The incandescent filtration is regarded as a most important feature of this invention, as it is believed that thereby certain chemical reactions are set up which result in the surprising yield of permanent gaseous product shown by trial. Zone 16 having been completely incinerated, the adjacent burner will then be ignited and the residual volatile matter in zone 17 will be completely expelled and, at the same time, the adjacent zone 18 will receive a similar relatively incomplete heat treatment. The heat treatment will likewise be progressively carried out from the escaping end of the retort to the farther end, until no further generation of gaseous product is realized. It will, of course, be understood that, in lieu of the single bale, a plurality of bales may be employed and treated in sequence in the same manner as in the foregoing case, although it may be stated that such single bale will in many cases be preferred, the invention is not to be limited in any respect to the manner in which the straw may be introduced into the retort, or the precise form of the same; thus, a pulverant mass may be employed, if so desired, in carrying out the invention.

In order that a suitable collection of by-products may be had and that such purification as may be desired may be made, a tar-condensing or receiving chamber 24 may be included in the course of the flow of the escaping products, and to separate out the more liquid products, commonly known as pyrolygneous acid, a condensing coil 25 is inclosed by a suitable water jacket 26 and is in connection at its lower end with a collection chamber 27, in order that the aforesaid liquid products may accumulate therein. To attain a suitable purification of the residual products, should this be deemed desirable, a number of chambers 28 and 29 containing lime or other suitable material may be interposed, and to finally receive the valuable gases, a large reservoir 30 will be positioned at the terminus of the escape conduit.

In commercially carrying out this invention, a plurality of retorts may be employed and the carbonization may alternately take place throughout the series, the escaping gaseous products being caused to pass through the incandescent mass in the last heated retort, which is maintained at a high temperature, and other variations in the manner of carrying out the process may be resorted to.

While I do not profess to be able to offer with certainty an infallible theory in explanation of the demonstrated facts of the process, still an opinion may be ventured in order to assist in clearing up the obscurity as far as possible. One cause of the extraordinarily high yield of the process appears to reside in causing the preliminarily formed gases to pass through the hot carbon which may be a portion of the straw mass before being ultimately discharged and may be attributed to some chemical changes that take place during such coursing of the gases, and, perhaps, also, to the gradual heating that is given the more distant portions of the mass by my mode of raising the temperature.

It may be that, by passing through an incandescent porous carbonaceous mass, the carbon dioxide, contained in the gases liberated by the decomposition of the straw, is converted into a valuable, permanent gas according to the following reaction: $\text{CO}_2 + \text{C} = 2\text{CO}$, while any steam may similarly be reduced.

In order to further utilize the invention, use may be made of charcoal from a previous charge of straw, which may be contained in the end of the retort farthest removed from the charging opening, or may be contained in a neighboring retort. The subsequent treatment of the crude gas, its purification, and the recovery of the by-products, such as tar and pyroligneous acid, methyl alcohol, etc., can be conducted by the well-known processes which have been long used in connection with the distillation of wood.

While I do not care to assign any particular temperature at which the process must be worked, it may be stated that, in such tests as I have made, a low yellow heat produced the best results, but, naturally, the precise degree of temperature will be dependent upon particular conditions. The best working temperature can be readily determined in a very few minutes by a trial run of the adopted apparatus while employing the desired variety of straw.

The element of the rate of distillation will, of course, vary in accordance with a great many factors and, for this reason, I cannot state any precise rate of working. One principle to be borne in mind is that each successive part be thoroughly carbonized before the next adjacent portion is heated. As conclusive to a general understanding of the manner in which the heat treatment may be carried out to realize any desired result, it may be stated, as a general rule, that the effect of a rapid application of heat is to liberate a relatively high percentage of fluid by-products, such as pyroligneous acid and tar, while the permanent gaseous product will be relatively low. If, however, the heat treatment proceeds at a slower rate, the converse obtains, in that the pyroligneous acid content is materially lessened, while the gaseous

product is correspondingly high. Accordingly, the treatment will be varied to obtain any predetermined product.

In carbonizing straw according to this invention and under the conditions stated, it has been observed that the charcoal remaining in the retort retains its original form and proportions and is converted into an exceedingly porous skeleton work, which, I believe, tends to materially assist the carrying out of the process in obtaining a high gaseous content from the straw. This porous, carbonized mass will be found to be capable of being used in a regenerative way in the retort as a satisfactory fuel, and is also well adapted for other purposes to which charcoal has heretofore been applied. Thus, I contemplate that, because of its porous nature, such carbonized mass may be employed very effectively in filtration plants.

As my process could be carried out with different ingredients and by varied steps without departing from the scope of my invention, I intend that all matter contained in the above description shall be interpreted as illustrative and not in a limiting sense.

I desire it also to be understood that the language used in the following claims is intended to cover all of the generic and specific features of the invention, herein-described and all statements of the scope of the invention, which, as a matter of language, might be said to fall therebetween.

Having described my invention, what I claim as new and desire to secure by Letters Patent is:

1. The art of generating a gas from a grammaceous mass comprising a carbonized, an uncarbonized and an intermediate partly carbonized portion, which consists in applying heat to the partially carbonized grammaceous mass at the portion intermediate the carbonized and uncarbonized portions thereof, whereby gas is generated at such intermediate portion and the uncarbonized portion is gradually heated preparatory to ultimate distillation.

2. The art of generating combustible gas which comprises compressing straw into compact bales and progressively subjecting successive portions of said compacted bales of straw to a source of heat, each portion being thoroughly carbonized prior to the heating of the next succeeding portion.

3. The art of generating a gas which consists in subjecting a mass of compressed straw filling a zone in a retort to a distilling temperature at a point between the feeding and discharge outlets of said retort, and exposing fresh straw to the effect of such distilling temperature at points successively removed from said discharge outlet.

4. The art of generating a gas substantially free from carbon dioxide, which consists in providing a zone of a distilling tem-

perature, subjecting a portion of a mass of straw to the influence of said zone of distilling temperature and causing a relative movement between said zone of distilling temperature and said straw in a direction such that the products of distillation pass on their way to a discharge opening through and have an intimate contact with the mass subjected to prior distilling temperatures.

- 10 5. The process of producing a combustible gas of high calorific power substantially free from carbon dioxide, consisting in obtaining a suitable quantity of a gramineous material in native or raw condition and in a relatively compact state, introducing said material into a closed retort, superheating said retort and contents to a distilling temperature meanwhile excluding air from the interior thereof, maintaining such distilling temperature until

substantially all the combustible volatile and gaseous products have been driven off from said material, withdrawing said products through a passage or zone maintained at a high temperature and filled with a porous incandescent highly carboniferous mass, whereby said products during said withdrawal will be positively compelled to thoroughly infiltrate through and be brought into intimate contact with said incandescent mass and be improved in quality thereby, and finally suitably storing the resultant gas.

In testimony whereof I affix my signature in the presence of two witnesses.

JAMES RUSSELL COUTTS.
